COMBINED BOW LIGHT AND PENNANT MAST

Thomas L. Faul, P.O. Box 48, Mottville, N.Y.

Filed Oct. 29, 1959, Ser. No. 58,120

Term of patent 14 years

(Cl. D48—31)

Fig. 1 is a front elevational view of a combined bow light and pennant mast showing my new design,

Fig. 2 is a top plan view thereof,

Fig. 3 is a side elevational view thereof, and

Fig. 4 is a reduced rear elevational view thereof with the mast omitted for convenience of illustration only.

I claim:

The ornamental design for a combined bow light and pennant mast, as shown.
